LUMINAIRE

Frank Van Steenhoven, 140 N. 5th St., Newark, Ohio

Filed July 26, 1963, Ser. No. 75,984

Term of patent 14 years

(Cl. D48—23)

FIG. 1 is a front perspective view of a luminaire showing my new design;

FIG. 2 is a top plan view thereof;

FIG. 3 is a rear elevational view thereof; and

FIG. 4 is a side elevational view thereof.

The dominant features of my design reside in those portions shown in full lines in the drawings.

I claim:

The ornamental design for a luminaire, substantially as shown and described.
